United States Patent Office

Des. 233,999
Patented Dec. 24, 1974

233,999

AERIAL TOY

John W. Potter, 3375 Rancho Del Monico,
Covina, Calif. 91722

Filed June 26, 1972, Ser. No. 266,485

Term of patent 14 years

Int. Cl. D21—01
U.S. Cl. D34—15 HS

FIG. 1.

FIG. 2.

FIG. 3.

FIG. 1 is a top plan view of an aerial toy, showing my new design;

FIG. 2 is a side elevational view thereof; and

FIG. 3 is a bottom view thereof.

The interior star feature and the generally radial diamond-shaped features are elevated above the central interior panel portion to extend outwardly toward the observer, as viewed in FIG. 1, a distance substantially less than the outward extension of the outer rim.

I claim:

The ornamental design for an aerial toy, as shown and described.
